UNITED STATES PATENT OFFICE.

WILLIAM C. VAN VLIET, OF NEW YORK, N. Y.

MACHINE FOR WIRING THE CORKED NECKS OF BOTTLES.

SPECIFICATION forming part of Letters Patent No. 352,168, dated November 9, 1886.

Application filed April 28, 1886. Serial No. 200,392. (No model.)

To all whom it may concern:

Be it known that I, WILLIAM C. VAN VLIET, a citizen of the United States, residing at New York city, county and State of New York, have 5 invented certain new and useful Improvements in Machines for Wiring the Corked Necks of Bottles, of which the following is a specification.

My invention relates to that class of machines which pass two wires around the neck of the bottle and two over the cork, and then 10 twist the ends of all four wires together on the side of the neck, after which the wires are severed close to the neck to permit the removal 15 of the wired bottle. A machine of this type is shown in the patents to Carpenter, March 25, 1884, No. 295,735, and No. 318,955, of June 2, 1885, on which my invention is an 20 improvement in several important features and in many details. In brief outline, the essential features of machines of this type consist of a rotary hollow spindle, through which the wires are drawn from a reel carried by one 25 end of the spindle and are fed toward a fixed socket at the front of the machine, in which the neck of the corked bottle is placed. Rotary pliers mounted on and revolving with the front end of the spindle have tubular or 30 perforated jaws, through which the two side wires are led around the neck of the bottle, while the two top wires pass straight between the jaws over the top of the corked neck, all 35 four wires being twisted together at the ends and held in stationary gripping-nippers placed in front of the neck-socket. When the neck 40 of the bottle is placed up in the socket between the jaws of the rotary pliers, the top wires are strained or bent over the top of the cork, and when the machine is now started 45 the spindle with its pliers first retreats back, thus passing the side wires around the neck of the bottle, and then revolves and twists all the 50 wires together at the rear of the neck, after which a cutter descends and severs the twisted ends, and the wired bottle is then removed. The pliers holding the severed and twisted 55 stub or ends of the wires now advance under the socket and insert the twisted stub in the stationary nippers, which firmly hold the 60 same ready to repeat the same operations for the next bottle inserted.

My improvements lie chiefly in the special

construction of the rotary pliers and their accessories for guiding and gripping the wires to give them the proper direction and tension 55 when passed over and around the neck and twisted thereon.

My invention also consists in novel means for rolling or bending down the projecting twisted ends of the wires flush on the neck of 60 the bottle, as hereinafter fully set forth and claimed, whereby a much more efficient machine is produced.

In the drawings annexed, Figure 1 presents a front end elevation of my improved machine, 65 and Fig. 2 is a plan view thereof, showing the parts in normal initial or starting position. Fig. 3 is a side elevation of the machine, and Fig. 4 is a sectional side elevation of the same. Fig. 4½ is a fragmentary plan of Fig. 70 4. Fig. 5 is a fragmentary side elevation, showing the bottle-neck, the neck-socket, and the spindle with its rotary pliers and accessories, illustrating the position of parts when the spindle has retreated with the wires 75 passed around the neck and ready for being twisted together. Fig. 6 is a fragmentary plan view of the same parts shown in the same position. Fig. 7 is a cross-section on line $x-x$ of Fig. 3, looking to the left, showing the gearing of the spindle and the connection of the wire-reel. Fig. 8 is a cross-section on line $y-y$ 80 of Figs. 2 and 3, looking to the right, and illustrating the cutters with their locking device. Figs. 9 and 10 are enlarged perspective views 85 of the neck of the corked bottle with the wiring as performed by this machine, Fig. 9 showing the wires just as the bottle leaves the wiring-socket of the machine after the twisting and severing operations, with the twisted ends 90 projecting radially from the neck, while Fig. 10 shows the finished stage, with the twisted ends bent or rolled down flush on the neck. Fig. 11 shows details of the mechanism for performing the last operation.

Referring to the drawings, $a-a$ indicate the top frame or table of the machine supported upon the legs $b-b$. At the front end of the frame there arises an overhanging arm, c , at the end of which is held the fixed semi-cylindrical socket d , in which the bottle-neck is inserted to receive the wiring action of the machine, as shown best in Figs. 1, 2, 3, 4, and 5. e indicates the rotary wiring-spindle of the

machine, which is in line with the socket *d*, but in a plane a little below the same, as shown in Figs. 3, 4, and 5. This spindle is supported in the bearings *a'*, which arise from the top frame, *a*, near the rear thereof, and it is free to revolve and slide back and forth in said bearings. Outside the bearings *a'* a pinion, *e'*, is rotatively engaged with the shaft by a spline, the shaft being free to slide through said splined pinion, which latter is retained in position by an encircling yoke, *e''*. A train of gearing engages with the pinion to revolve the same and rotate the shaft, which will be hereinafter explained.

15 The rotary twisting-pliers are fixed on the front end of the spindle *e*, and consist of these main parts—viz., the body or cross-head *F* of the pliers, which is screwed fixedly on the end of the spindle, (see Figs. 2, 4, 5, and 6,) the 20 plier-jaws *G*, pivoted on the cross-head, and the "leader" *H*, placed in the cleft of the cross-head and between the jaws of the pliers. The plier-jaws have short curved arms, which project forward and converge together beneath the bottle-socket *d*, the curve of the jaws being sufficient to encircle the neck of the largest bottle which is expected to be wired. The 25 long arms of the jaws are nearly straight, and project backward and slightly diverge, and are provided with rollers on their tips, as shown best in Figs. 2 and 6. On the rear end of the spindle is mounted the reel-frame *B*, which carries the four spools, *f*, from which the four wires are drawn, and which thence pass individually through four distinct guide-tubes in the base of the spindle, as seen best in Figs. 2 and 7. The front ends of two of these tubes are bent into diagonal holes bored through the sides of the cross-head *F*, as seen in Figs. 2, 4, 30 and 5, through which holes the wires *g g* issue on each side of the cross-head, thence pass through diagonal holes in the plier-jaws near the pivots thereof, and, being thence led around the outside of the curved arms, finally enter 35 a hole near the tips of the jaws, (see Figs. 2 and 3,) and issue between the meeting tips thereof, as seen in Figs. 2 and 6, said wires *g g* being those which are passed around the neck of the bottle. The wires *h h*, however, which 40 are passed over the top of the cork, issue directly from the guide-tubes in the end of the spindle and pass straight through the center of the pliers, being guided first over a self-adjusting or pivotal clamping-anvil, *i*, resting on 45 an angular seat on the leader *H*, and under a small clamping-lever, *k*, and thence pass through the twin tubular guides or nostrils *l l* on the tip of the leader, and finally project between the meeting jaws of the pliers together 50 with the wires *g g*, where all are now twisted together and are held in the jaws of the gripping-nippers, *I*, which are mounted on the overhanging arm *c* in front of the socket *d*.

Now, upon the spindle *e*, behind the head *F* of the pliers, is mounted a loose clutching-head, *K*, which has a constant rotative engage-

ment with the pliers and the spindle by means of the pin *j*, which projects from the clutch-head and passes through a perforated lug on the plier-head. A spring, *j'*, encircling the 70 rod *j*, tends constantly to throw the pliers and spindle forward and the clutch-head backward. The outer end of the rod *j* is tubular and incloses a bolt-spring, *n'*, and bolt *n*, which projects into proximity to the upright arm of 75 the clamp-lever *k*. The stem *q* of the leader *H* passes loosely through a bore in the opposite side of the head *F*, and its end projects into a socket in the clutch-head *K*, in which is enclosed a spring, *q'*, which tends constantly to 80 press the leader forward, the movement one way or the other being limited by a pin, *3*, in the clutch-head engaging a slot, *4*, in the leader-stem. Passing radially through the clutch-head is a clutching-bolt, *o*, which is adapted to 85 engage at one position with a hole, *o'*, in the spindle, and thus lock the clutch-head to the spindle. A spring trigger-lever, *p*, engages this bolt *o*, and by the action of its spring tends constantly to press the bolt into engagement, which will occur, however, only at the 90 point when the spindle and pliers have been slid fully back ready to commence the twisting operation, as seen in Fig. 5.

The trigger-lever *p* projects radially from 95 the clutch-head and in the path of a projection, *p'*, on the frame *a*, near the forward end of the stroke of the spindle, so that when the spindle and pliers slide forward after the twisting and severing operations the trigger-lever strikes the projection *p'*, so as to withdraw the bolt and release the clutch-head, when the parts spring back to their initial positions, as seen in Figs. 3 and 2.

It may now be seen that when the machine 105 is in the initial or starting position, as seen best in Figs. 2 and 3, the rotary pliers will be advanced under the socket *d*, with the tip of its jaws close to the gripper-nippers *I*, while the nose of the leader *H* will lie close 110 up to a downwardly-projecting flange or abutment, *m*, which is fixed in the rear of the socket *d*, and the two top wires, *h h*, will issue straight from the leader and pass close under the edge of this flange, and extend diametrically across under the socket, (see Figs. 5 and 2,) passing between the jaws of the rotary pliers and into the grip of the fixed nippers *I*, in which the twisted end of all four wires will 115 be held, as before stated. The parts being, therefore, in the position described, the corked neck of the bottle is now thrust up into the socket so that the base of the glass lip or rim on the neck is level with the top of the plier-jaws, and flush, or nearly so, with the base 120 edge of the abutment *m*, and it will be seen that by this action the two top wires, *h h*, will become stretched over the top of the cork, and bent down on each side of the neck, as seen in Fig. 5, the flange *m* serving as a fixed 125 definite base edge to determine the bend of the wires at the right point over the neck,

and to keep the wires close to the base of the lip, and in a straight line from that point to the leader, so as to be in a plane almost parallel with the side wires, *g*. The machine is now started, so as to impart the automatic motions to the spindle, the first movement of which will be to retreat or slide backward without rotating, and this will cause the plier-jaws to open, straddle, and slip around the neck of the bottle below the lip thereof, thus passing the side wires, *g g*, around the neck until the plier-jaws meet again at the rear of the neck, just under the flange *m*, as seen in Figs. 4 and 4½, when all the wires will now be passed over and around the neck. At this point the meeting plier-jaws will now have moved back close to the nose of the leader *H*, as seen in Fig. 4½, and the head *F* of the pliers moving back against the spring *j'* will have pressed the clutch-head *K* back against the bearing *a'*, and the back of the head *F* will also strike a pin, *j''*, in the stem of the leader *H*. Now, up to this point the wires which had all been held loosely to allow of their paying out freely to the bottle now become clamped preparatory to becoming strained or tightened by the terminal sliding motion of the spindle previous to the rotation to twist the wires. The side wires, *g g*, become clamped between the tips of the plier-jaws, which are closed thereon by the riding up of the roller-tipped plier-arms onto the inclined lugs 2 2, projecting from the clutch-head *K*, as seen in Fig. 6, while the top wires, *h h*, become simultaneously clamped between the anvil *i* and clamp-lever *k*, as the arm of the latter is forced back against the spring-bolt *n*, as seen in Fig. 5. The terminal sliding motion of the spindle and pliers will therefore now draw upon the clamped wires, thus putting the necessary tension thereon to strain them tightly over the cork and around the neck of the bottle, and to pull them straight and taut from the abutment *m* to the nose of the plier and leader, as seen in Figs. 6 and 5, preparatory to twisting the same.

It will be seen that the several springs *j'*, *n'*, and *q'* will allow the terminal sliding motion of the several parts to strain the wires after they have been clamped, which would not be allowed if the parts were rigid. At the instant that the spindle arrives at the end of its stroke the hole *o'* in the spindle will be brought in register with the clutch-bolt *o* of the clutch-head, which bolt will at once fly into engagement, and thus lock the head to the spindle and retain the pliers and other parts in their contracted or closed positions, holding the wires tense. Immediately after this the spindle is revolved by the automatic action of the cams and gearing, and the four wires are thus twisted firmly together between the neck of the bottle and the tips of the pliers, the spindle making five revolutions for this purpose. At or near the end of this twisting operation the cutters *r r'*, which are arranged

back of the abutment *m*, and about half-way between the neck of the bottle and the pliers, descend and sever the twisted wires at about the middle of their length, thus leaving a small twisted projection on the neck of the bottle standing out radially, as seen in Fig. 9, and also leaving a small twisted stub projecting from the jaws of the pliers. As soon as the severing takes place, the bottle is instantly withdrawn from the socket, and appears as seen in Fig. 9. Immediately after this the spindle, with its pliers and clutch-head, &c., moves directly forward, and the pliers, passing under the socket as at first, finally insert the twisted stub of wires in the gripper-nippers *I*, which now close on and hold the same, as seen in Fig. 2, while about the same instant the trigger-lever *p* strikes the projection *p'*, and thus withdraws the bolt *o* and unclutches the head *K* from the spindle, so that the spring *j'* now throws the head *K* back, and thus causes the lugs 2 2 to retract from the plier-jaws, and the bolt *n* to retreat from the clamp-lever *k*, as seen in Fig. 3, thus allowing the pliers to open and the clamp to relax, and thus leaving the wires free as at first, and thereby bringing the parts back to the initial position ready for the wiring of the next bottle.

Now, the automatic mechanism for imparting the reciprocating and rotary motions to the spindle at the proper moment is substantially the same as shown in the Carpenter patent before cited, but may be here briefly described for a better understanding of the whole machine—that is, referring to Fig. 2, 5 indicates the driving-pulley of the machine, to which the power is applied, and which is fixed to one end of a short shaft provided at the upper end with a pinion, 6, which gears with a bevel-wheel, 7, which is mounted on the main cam-shaft 8 of the machine. This wheel 7 is loose on the shaft 8, but fitting close against the same is a clutch-hub, 9, which is keyed to the shaft and provided with a sliding clutch-bolt, 10, the inner end of which is adapted to engage with an engaging-recess in the wheel 7, while the outer end has an overhanging head which is normally engaged by the wedge-tip 12 of a clutch-lever, 13, which is connected to the treadle 14, (see Figs. 1, 2, and 8,) so that said wedge-tip keeps the bolt 12 withdrawn against the action of the spring 15. (See Fig. 2.) As soon, therefore, as the treadle is depressed, the wedge 12 is withdrawn from the bolt 10 and the bolt flies into engagement with the constantly-revolving wheel 7, which therefore becomes clutched to and revolves the cam-shaft 8. The large cam 16 on the shaft engages a roller on the lever 17, which is connected by link 18 with the sliding yoke 19, which engages a collar, 20, on the spindle *e*, and thus imparts the necessary reciprocating motion to the spindle, the cam being of course properly formed to impart the correct motion at the right times in the same way as heretofore. Upon the end of the cam-shaft is fixed

a gear-wheel, 21, which meshes with a clutch-pinion, 22, which is loose upon a stud, 23. Upon the stud, close to the clutch-pinion, is mounted the gear-wheel 24, which meshes 5 with the pinion e' on the spindle e .

Referring now to Figs. 4 and 7, a spring-impelled clutch-bolt, 25, projects through the hub of wheel 24, and is adapted to engage with a recess in the pinion 22, but is normally 10 withdrawn and engaged by the wedging-tip of a cam-lever, 26, (see Figs. 2 and 7,) which is actuated by a small eccentric or cam, 27, on the main shaft 8, back of the wheel 21. The relation of these parts is such that just as the 15 spindle has been slid fully back ready to commence the twisting operation the cam 27 moves the clutch-lever 26 out of engagement with the bolt 25, which at once flies into engagement with the pinion 22, so that rotary motion 20 is now imparted to the gearing to revolve the spindle. In this operation the spindle will make five revolutions, and the wheel 24 and pinion 22 will make just one revolution, and as the wheel 24 arrives near the end of 25 its revolution the cam 27 will bring the lever 26 into engagement with the bolt 25, and thus withdraw the same from the clutch-pinion 22, allowing the same to revolve loosely, as before, while the head of the bolt will project over the 30 top of the frame a , as seen in Fig. 2, and thus stop further rotation of the wheel in that direction, while at the same instant an inclined projection, 28, on the wheel 24 will catch behind a spring-bolt, 29, (see Figs. 2, 3, and 4,) 35 and thus stop rotation of the wheel in either direction, and thereby hold the spindle firmly in its initial position at the end of its fifth revolution, preventing it from turning in either way, but allowing it to go through its sliding 40 movements when impelled by the cam 16 at the next action, as will be understood.

The cutters for severing the wire and the device for operating and locking the same are shown best in Fig. 8. The cutters consist, as 45 usual, of two elbow-levers, r r' , pivoted together just back of the flange m of the socket d , with their cutting-blades facing each other like shears, and projecting down in a position to grasp and sever the wires when twisted between the neck of the bottle and the pliers, as 50 also seen in Figs. 2, 4, and 5. The lower lever, r , of the cutters is pivoted on a fixed pin, r^3 , which projects from the overhanging arm e , while the upper arm, r' , is jointed to a vertical sliding rod, s , provided with a projection, s' , which at the right moment is engaged by a cam, t , on the front end of the cam-shaft 8, which cam depresses the rod, and thus operates the cutter-levers. Parallel with the sliding rod s is arranged a locking-lever, u , which 55 is pivoted on the same pin r^3 with the cutter-lever r , and the upper arm of this locking-lever is notched, so as to engage with the pin r^2 , which joints the rod s to the lever r' when 60 the cutters are raised to their upper limit of motion, and thus locks the cutters in their said

raised or quiescent position. The lower arm of the locking-lever u projects in the path of the cam t , and is provided with a spring, u^2 , which tends to constantly throw the lever into its locking position. When, however, the cam t revolves, it will first sway the locking-lever out of its path, and thus remove its notched locking end from engagement with the pin r^2 , and the cam will then engage the projection s' and depress the rod, and as the pin r^2 is compelled to move along the edge of the lever u the cutters will be moved down bodily in an arc struck from the pin r^2 , and the blades will be simultaneously closed together as they move down, thereby straddling the twisted wires and severing the same about half-way between the bottle-neck and the rotary pliers, as will be understood from Figs. 2 and 8. When the cam t passes the projection s' , the spring s^2 throws the rod s and cutters r r' up to their normal positions, and the spring u^2 throws the locking-lever into engagement with the pin r^2 , as shown by full lines in Fig. 1, thus locking the cutters firmly in place, and preventing the possibility of their moving into the way of the pliers. The spring s^2 cushions the up motion of the rod s and its attached parts.

Referring to Figs. 1 and 2, it will be seen 95 that the two jaws of the gripper-nippers I are pivoted to a U-shaped guide-piece, 30, which is mounted on a curved pin, 31, projecting from the overhanging arm c , and a link, 32, riveted over the front of the jaws holds the nippers pivotally to the piece 30. The tails of the nipper-jaws straddle the pivoted wedging-block 33, which is connected by an adjustable rod, 34, with the reciprocating yoke 35, which is guided in the frame a and actuated 105 by a cam, 36, on the front end of the shaft 8. It will therefore be seen that by this cam mechanism the block 33 will be partly turned at the proper moment, so as to spread the tails of the nipper-jaws, and thus close the gripping-edges to grasp the twisted wires, while when the block is turned in the reverse way by the return action of the cam the U-shaped spring 37 will open the jaws and permit the removal of the wires when the wiring operation is finished. The nuts 39 allow of adjusting the length of the rod 34, so as to regulate the grasping motion of the pliers. The nippers, being mounted on the curved pin 31, are thus capable of a bodily movement to and 115 from the socket d in an arc concentric with the curve of the pin, or about central with the block 33, and a spring, 38, tends constantly to draw the pliers inward close to the socket, so that by this means the nose of the gripping-nippers will always be brought into the path of the rotary pliers G, when it advances toward the nipper holding the stub of the twisted wires, so that the twisted stub will not only be now inserted in the jaws of the nippers, but 120 the nose of the pliers will press up close against the nippers and force the same outward a lit-

tle beyond the socket, as seen in Fig. 2, thus compelling the nippers to take firm hold on the stub of wires as close as possible to the nose of the rotary pliers, which is a great advantage.

Now, referring to Figs. 2, 3, 4, and 7, it will be seen that the reel B is made with a light open metallic frame, through which are passed shouldered bolts, on which the bobbins *f f* are mounted, each of which bobbins may have a retarding or tension spring, if desired. Over the removable end of the bolts is pivoted a turn-button, *f'*, whereby the bolts are held in place, or may be removed to allow of the removal and renewal of the bobbins, as will be readily understood. Now, this reel is not mounted rigidly on the spindle, as heretofore, but it is mounted loosely thereon, and upon the end of the spindle is fixed a collar or yoke, *v*, carrying a semicircular rod, *v'*, curved concentric to the spindle, and on which are placed two spiral springs, *v²*, while from the hub of the reel-frame projects a radial arm, *w*, which encircles or straddles the curved rod *v'*, between two washers, *w'*, against which the springs *v²* respectively bear, as seen best in Figs. 2 and 7. A yielding rotative connection or centrifugal cushion is thus formed between the reel and the spindle in both directions of rotation, so that when the spindle is suddenly started or stopped the inertia and momentum of the reel with its heavy bobbins is thus cushioned and relieved, thereby preventing any hard shock from being imparted to the spindle or its gearing, which would otherwise occur, and which was very injurious to the machine as heretofore made. This feature, however, with others herein shown, I do not claim as my invention, and they will form the subject of a separate application.

It will now be seen that my present machine is not only an improvement in several important details over the former machines of this kind, particularly in the rotary pliers with its wire leader, &c., and an important feature is, that in this machine the two top wires are guided in a spread or separated position in parallel guiding-nostrils from the mouth of the pliers, and thus pass over the cork in two spread or separated parallel strands, which, as is well known, gives much greater holding power on the cork and is less likely to cut into the same than is the case when the two top wires are twisted together over the cork.

All the operations for wiring the bottle having been now explained, it will be understood that when the bottle is removed from the machine it will appear as in Fig. 9, with the twisted ends of the wires projecting radially from opposite sides of the neck, and as it is not desirable to have the ends project in this manner, a final operation is resorted to for rolling down the same flush with the neck of the bottle, as seen in Fig. 10. The device for performing this final operation is shown on the left-hand side of the machine in Fig. 1, and in

details in Fig. 11, and consists of a fixed socket-head, *D*, having a central socket, *y*, into which the wired neck of the bottle is inserted. This socket is lined by four spring-tongues, 70 41, which embrace the bottle-neck when inserted, two of these tongues being notched or formed with hooked or outcurved claws 42 on their free ends, against which the projecting twisted ends of the wires will rest when the 75 bottle-neck is placed in the socket, as shown by dotted lines in Figs. 1 and 11. Now, this fixed socket-head *D* is secured to the end of a long stud, 44, (see Fig. 2,) which is secured to and supported by a bracket-arm, 45, extending from the side of the main frame of the machine, as shown in Figs. 1 and 2. On the stud, between the bracket 45 and socket-head *D*, is mounted a grooved pulley, 46, which is free to revolve thereon, and is driven by a belt, 80 47, from a grooved rim on the main pulley 5, as well shown in Figs. 1 and 2. Two lever-arms, 48, are pivoted on the front of the pulley 46, (see Figs. 1 and 2,) and project over the front of the socket-head, and to said levers are jointed 85 the bars 49, carrying rollers 50, which approach the socket at opposite sides thereof. On the front of the socket-head *D* is a cam-groove, *d'*, which is engaged by rollers on the levers 48. The levers 48 bear on the bars 49 90 in an elastic manner by the interposed springs 51, which encircle studs extending from the bars and provided with adjustable nuts 52, resting on the levers 48. Now, when the wired neck of the bottle is inserted in the spring-socket *y*, with the twisted ends of the wires projecting over the spring-claws 42, as shown by dotted lines in Fig. 1, the machine being in motion so as to revolve the pulley 46, it will be seen that as the pulley revolves the action 95 of the cam *d'* will sway the levers 48 and bars 49 to and from the central socket, thus causing the rollers 50 to press against and roll over the projecting ends of the wires, and thereby bending the same over the spring-claws 42 in 100 a curved line close to the neck of the bottle, or as close as the thickness of the spring-claws will allow, which is practically flush with the neck of the bottle, as seen in Fig. 10, which represents the neck after it has been removed 105 from the spring-socket. This operation requires but a few seconds to insert the bottle in the spring-socket and remove it therefrom, and it will be seen that as the pulley 46 is driven directly from the main pulley 5 the bending 110 device is thus revolving constantly while power is applied to the pulley 5, although the wiring mechanism may be at rest, so that no starting or stopping operation is necessary in using the bending or rolling device; and, furthermore, it will be seen that as the bending 115 device is in convenient position on the left to receive the neck of the bottle just after it is removed from the wiring-socket, no time is unnecessarily lost in performing the several operations of the machine, thus enabling the 120 wiring to be performed rapidly and without 125 130

the defects heretofore experienced. In this bending device the essential feature is the receiving-pocket with the projecting claws on which the wires rest, with a rotating bending device to roll or press against the wires and bend the same over the projections against the neck of the bottle, so that I do not confine myself to the precise combination of devices shown, as they may be varied without departing from the essential feature. I do not confine myself to the particular form of the clutching devices of the clutching-head K, as any equivalent devices may be used.

15. What I claim as my invention is—

1. In a corked-bottle-wiring machine, substantially such as set forth, the combination, with the rotary wiring-spindle and the rotary twisting-pliers mounted thereon, of two parallel wire guides or nostrils at the center of the pliers adapted to issue two wires in separate parallel strands over the top of the bottle-cork, substantially as herein set forth.

2. In a bottle-wiring machine, the combination, with a fixed socket to receive the neck of the bottle and nippers mounted in front of the same, of a rotary spindle and rotary pliers placed back of the same, a reel supplying four wires, wire-guides leading circumferentially to and through the tips of the plier-jaws, through which two of the wires are led to issue at the tips of the jaws, and two parallel wire guides or nostrils arranged at the center of the pliers, and adapted to guide and issue the two remaining wires in two separate parallel strands in a diametrical position relatively to the other wires, all said wires being twisted together at the tips of the plier-jaws, and held by the said nippers, substantially as and for the purpose herein set forth.

3. In a bottle-wiring machine, the combination, with a rotary spindle, of the rotary twisting-pliers formed with the head F, jaws G, and wire-guides arranged to guide two wires circumferentially around the jaws to issue at the tips, with the yielding or movable leader H, arranged at the center of the pliers, and

having wire-guides arranged to issue wires diametrically between the jaws of the pliers, substantially as herein set forth.

4. In a bottle-wiring machine, the combination, with the spindle e, clutch-head K, and pliers F G, of the leader H, having the wire-guides l, and the sliding stem q, passing through the head of the pliers and having an elastic or spring abutment in the clutching-head, with a stop, 4, to limit its play in the clutch-head, and a stop, j', to engage the head of the pliers, substantially as shown and described.

5. Means for bending the twisted ends of wires upon the necks of bottles, consisting of a socket into which the bottle-neck is placed, provided with projections over which the wires lie, with a rotary rolling or bending device arranged to revolve around the socket in the path of said wires, and to thereby bend the same over the projections against the neck of the bottle, substantially as set forth.

6. The combination, with the fixed head D, having the socket y, provided with the projecting points or springs 41, of the rotary head or pulley 46, carrying a radially-vibrating bending device or devices arranged to approach to and recede from the socket, substantially as set forth.

7. The combination, with the fixed head D, having the socket y, of projections or hooks 41, and cam d', with the rotary head or pulley 46, carrying yielding bending devices, engaged with said cam and arranged to vibrate to and from said socket as the pulley revolves, substantially as shown and described.

8. The combination, with the fixed head D, with the socket y, hooks 42, and cam d', of pulley 46, carrying the levers 48, engaged with said cam, bars 49, pivoted to said levers, and holding the rollers 50, and a yielding connection between said bars and levers, substantially as shown and described.

WM. C. VAN VLIET.
